DISPENSING CONTAINER

Filed Dec. 21, 1927

Patented Nov. 13, 1928.

1,691,861

UNITED STATES PATENT OFFICE.

HARRY S. STOUT, OF HUNTINGTON, WEST VIRGINIA.

DISPENSING CONTAINER.

Application filed December 21, 1927. Serial No. 241,739.

This invention relates to a dispensing container.

An object of the invention is the provision of a container for readily dispensing semi-fluids and in which a combined lever and cap is employed for revolving a high pitched screw whereby a slight turn of the lever will cause a rapid advance of the plunger within the container for forcing fluids from the container.

A further object of the invention is the provision of a dispensing container in which a plunger is employed for forcing a semi-fluid from a restricted opening by means of a high pitched screw, the same being in turn operated by a combined cap and lever connected with a rotatable cover, the lever establishing a greater leverage so that screws of higher pitch may be employed for the purpose.

This invention will be best understood from a consideration of the following detailed description in connection with the accompanying drawings; nevertheless, it is to be understood that this invention is not confined to the disclosure being susceptible of such changes and modifications as shall define no material departure from the salient features of the invention as expressed in the appended claims.

In the drawings:—

Figure 1 is a view in perspective of a dispensing container constructed according to the principles of my invention.

Figure 2 is a vertical section of the same,

Figure 3 is a fragmentary vertical section through part of the operating mechanism of the dispensing apparatus,

Figure 4 is a view in perspective of the rotatable closure for the container,

Figure 5 is a horizontal section taken along the line 5—5 of Fig. 2.

Referring more particularly to the drawings 10 designates a container or cylinder having the lower end open which is adapted to be closed by a flange cap 11 having an annular flange 12 embracing the lower end of the container and abutting a shoulder 13. The outer surface of the container is ribbed, as shown at 14, whereby the container may be readily held in the hand for a purpose which will be presently explained. The upper end of the container is closed, as shown at 15 and is provided with a central passage 16. The top 15 is extended, as shown at 17.

A screw 18 having high pitched threads is mounted axially of the container and re-

ceives the internal threads on a centrally disposed passage 19 of a piston 20. This piston has a packing 21 and an annular groove in the periphery which engages the inner wall of 60 the container 10.

The upper end of the screw is formed into a head 22 having a central passage 23 which opens into a radially disposed passage 24. The head is provided with an annular flange 65 25 which has a down turned knurled portion 26 from which extends laterally disposed lugs 27 adapted to engage beneath the under face of the flange or extension 17. The top 15 of the container adjacent the central passage 16 70 is provided with an inclined seat 28 adapted to receive a similarly formed portion on the head 22 in order to provide a tight fit between the top 15, the head 22 and the upper portion 29 of the screw 18.

An arcuately shaped lever 30 is pivoted on a pin 31 supported by the annular flange 25 and a coil spring 32 is located between the lever 30 and a head 33 of the pin 31. This lever is provided with a finger piece 34 for 80 operating said lever and for rotating the flange 25.

A cap or closure 40 is adapted to be seated upon the upper reduced end of the head 22 for closing the outer end of the passage 23 85 and maintained in place by an arm 41 secured to the lever 30. The inner end of the lever, as shown in dotted lines at 42 in Fig. 4 is adapted to abut a shoulder 43 on the head 22 and maintain said lever in the position shown 90 in said figure when the member 25 is revolved.

The outer ribbed surface 14 of the container may be provided with a section 50 for the application of the name of the ingredients contained therein. Another section may be provided, as shown at 51, having an arrow 52 to indicate the direction the lever and likewise the cap 25 may be rotated.

The operation of my device is as follows:

Pressure is applied to the finger piece 34 by means of the thumb while grasping the ribbed surface of the container in the hand, whence the lever 30 will be moved to the position shown in Fig. 4, thereby releasing the cap 40 from the passage 23 while at the same time causing rotation of the head 22 and likewise the flange or cap 25. Rotation of the head causes rotation of the screw 18 whereby the plunger 20 will be moved towards the upper end of the container and force semi-fluids contained therein through the passage 23.

A reverse rotation as indicated by the ar-

row in Fig. 1 will cause the plunger to be moved towards the opposite or bottom of the container and the cap 11 may be removed and likewise the plunger. The materials are 5 then filled into the container with the cap 40 in position closing the passage 23 after which the plunger is then applied to the threads of the screw 18 and moved inwardly of the extreme lower end of the container. The cap 10 then is applied and the lever 30 may be moved to an operative position for rotating the head 22 and likewise the screw 18, so that the plunger 20 may be moved as desired for forcing portions of the semi-fluid from the container.

It will be noted that the coil spring 32 has one end, as shown at 50, secured to the head 33 of the pin 31, while the other end of the spring is secured at 51 to the lever 30, so that 20 when the lever is moved to the position shown in Fig. 4 and released, the spring will return said lever to its normal position whereby the cap 40 will close the opening 23.

I claim:

- 25 1. A dispensing container comprising a barrel, a screw within the barrel, a piston having means engaging threads of the screw whereby rotation of the screw will cause movement of the piston longitudinally of the barrel, a dispensing head mounted for rotation on one end of the barrel and rigid with the screw, said head having a discharge passage for liquids, a closure for said passage, a lever pivotally connected with the head for 30 moving the closure to an inoperative position, while providing means for manually rotating the head and likewise the screw.
2. A dispensing container comprising a barrel, a screw within the barrel, a piston 40 having means engaging threads of the screw whereby rotation of the screw will cause movement of the piston longitudinally of the barrel, a dispensing head mounted for rotation on one end of the barrel and rigid with the screw, said head having a discharge pas- 45

sage for liquids, a closure for said passage, an arcuately shaped lever pivotally mounted on the head, said closure being rigidly connected with the lever, said head being provided with an abutment, the lever having one end adapted to engage the abutment for restricting pivotal movement of said lever so that when the lever is moved to a predetermined position the head may be revolved.

3. A dispensing container comprising a barrel, a screw within the barrel, a piston having means engaging threads of the screw whereby rotation of the screw will cause movement of the piston longitudinally of the barrel, a dispensing head mounted for rotation on one end of the barrel and rigid with the screw, said head having a discharge passage for liquids, a closure for said passage, a lever pivotally mounted on the head, means connecting the lever with the closure, said lever adapted to be moved to an operative position for rotating the head while causing the closure to be located in an inoperative position, and resilient means for maintaining the lever in contact with the head.

4. A dispensing container comprising a barrel, a screw within the barrel, a piston having means engaging threads of the screw whereby rotation of the screw will cause movement of the piston longitudinally of the barrel, a dispensing head mounted for rotation on one end of the barrel and rigid with the screw, said head having a discharge passage for liquids, a closure for said passage, a lever connected with the head for moving the closure to an inoperative position, while providing means for manually rotating the head and likewise the screw, and a resilient means for moving the lever to an inoperative position and for moving the closure into engagement with the passage.

Signed at Huntington, in the county of Cabell and State of West Virginia, this 19th day of December, A. D. 1927.

HARRY S. STOUT.
